(57) **CLAIM**

The ornamental design for a food package as shown and described.

DESCRIPTION

FIG. 1 is a front side perspective view of a food package in accordance with the disclosed subject matter.

FIG. 2 is a back perspective view of the food package shown in FIG. 1.

FIG. 3 is a front plan view of the food package shown in FIG. 1.

FIG. 4 is a back plan view of the food package shown in FIG. 1.

FIG. 5 is a left side view of the food package shown in FIG. 1.

FIG. 6 is a right side view of the food package shown in FIG. 1.

FIG. 7 is a top view of the food package shown in FIG. 1; and,

FIG. 8 is a bottom view of the food package shown in FIG. 1.

The broken dot-dash lines showing a second package in FIGS. 1-8 are included for the purpose of illustrating environmental structure; the broken lines form no part of the claimed design.

1 Claim, 6 Drawing Sheets
